CLAIM

The ornamental design for a tread of an automobile tire, as shown and described.

DESCRIPTION

FIG. 1 is a perspective view of a tread of an automobile tire showing my design;
FIG. 2 is a front view thereof;
FIG. 3 is a top view thereof;
FIG. 4 is a right side view thereof;
FIG. 5 is a left side view thereof;
FIG. 6 is a fragmentary enlarged front view showing the details of the tread thereof; and,
FIG. 7 is a section view taken along line 7-7 in FIG. 6.
The broken lines show portions of the tire that are not being claimed, and thus form no part of the claimed design.
